FOREIGN PATENT DOCUMENTS

WO WO 00/01028 1/2000

Primary Examiner — John Windmuller(74) *Attorney, Agent, or Firm* — Patterson Thuente Pedersen, P.A.(57) **CLAIM**

I claim the ornamental design for a circular tri-level antenna, as shown.

DESCRIPTION

FIG. 1 is a perspective view of a circular tri-level antenna according to my new design;

FIG. 2 is a top plan view of the circular tri-level antenna of FIG. 1;

FIG. 3 is a bottom plan view of the circular tri-level antenna of FIG. 1;

FIG. 4 is a left-side view of the circular tri-level antenna of FIG. 1;

FIG. 5 is a right-side view of the circular tri-level antenna of FIG. 1;

FIG. 6 is a front elevation view of a circular tri-level antenna of FIG. 1; and,

FIG. 7 is a rear elevation view of the circular tri-level antenna of FIG. 1.
